UNITED STATES PATENT OFFICE.

BRENT McM. REED, OF ARLINGTON, MARYLAND.

METALLIC TIME-CARD FOR LETTER-BOXES.

SPECIFICATION forming part of Letters Patent No. 354,439, dated December 14, 1886.

Application filed June 17, 1886. Serial No. 205,408. (No model.)

To all whom it may concern:

Be it known that I, BRENT McM. REED, a citizen of the United States, residing at Arlington, in the county of Baltimore and State 5 of Maryland, have invented certain new and useful Improvements in Metallic Time-Cards for Letter-Boxes, of which the following is a specification.

My invention relates to a metal time-card 10 for street letter-boxes, and has for its object to provide metal time-figures which are changeable or adjustable in a frame, whereby the same figures may be recombined to express different time as often as desired.

15 The invention is illustrated in the accompanying drawings, in which Figure 1 is a front view of the time-card and figures complete. Fig. 2 is a front view of the frame without the figures. Fig. 3 is a back view of the device 20 complete, excepting only two of the clamping-plates. Fig. 4 is a cross-section view of the frame. Figs. 5, 6, and 7 are views of the time-figure plates. Figs. 8 and 9 are views of locking-bars.

25 The letter A designates a metal frame of any suitable shape, provided on its rim b with two or more screw-holes, c, through which are passed screws for attaching it to the letter-box. Certain portions of the front surface of 30 the frame are smooth, and may be provided with raised letters cast integral therewith to give any desired announcement. For instance, at one upper corner is "Open A. M.," indicating that letters are taken from the letterbox at certain hours, which are shown directly 35 below. At the other upper corner is "Open P. M." The time-figures directly below "A. M." and "P. M." refer to work-days. In the lower left-hand corner is "Sunday," and the 40 time-figures on the horizontal line therewith refer to that day only. At the central part are the cast letters and words "U. S. Mail," and any additional announcement that may be desired. The rim b is continuous without 45 break, but cut-away places d are made in the plate, in which are to be inserted the time-figures e e'. At the back the rim b projects from the central surface, so that the entire central surface forms a recess, f. At one edge of 50 each cut-away place the back has a lug, g, cast integral therewith, and the plate of each hour-figure e has at one corner a notch, g', corre-

sponding in shape and size with the said lug. The purpose of the lug and notch is to insure that the hour-figure plate e, which must be inserted at the back, will be placed right side up. 55

The hour-figure plate e and the minute-figure plate e' are separate, and are provided with means for their union, so as to permit them to be changed and recombined to produce any desired hour and minute. The construction of these time-figure plates is shown in Figs. 5, 6, and 7.

Fig. 5 shows three views of the hour-figure plate—a front view, an edge view, and a back view. That portion e of the plate (see Fig. 5) on which the hour-figure is cast is thickest. At the end where the notch g comes the plate has a thin flange, h, which rests upon the back of the surface f, and the other end of the thick 70 portion is a thin minute-figure back, i, which has a tongue, k, at the extremity and a hole, l, at the center.

The minute-figure plate e' is shown in Fig. 6 in three views. This plate is thickest where 75 the minute-figures 25 are cast; but while thickest, this part is only about half as thick as the thick portion e of the hour-plate. At one end and flush with the back side of the thick part is a central tang, l', which, as in Fig. 7, is entered through the center hole, l, in the hour-figure plate. The minute-figure plate rests upon the thin part i of the hour-figure plate, as seen in Fig. 7. Said thin part i thus serves as a back or support for the minute-figure 85 plate. This plate has at the other end two tangs, n, one being at each corner, and said tangs are also flush with the back side. It will thus be seen that the construction is such that any hour-figure plate and any minute-figure plate may be combined, whereby a given set of plates permit of being changed and adjusted at will to express different time. 90

The time-figure plates occupy the cut-away places d in the frame, and the thin flange h at 95 one end of said plate and the tongue k and two tangs n at the other end rest upon the back f of the frame. These plates are confined to this position by a locking-bar, o, which extends across their backs. One end of the locking-bar o has a slot, p, and the other end has a slot, p', with an enlargement or wide opening, q, at one of its ends. The back of the frame has two headed studs, r, and the

slots p and p' of the locking-bar o engage with the said studs, as shown in Fig. 3. The locking-bar is placed in or removed from its position by being moved endwise.

5 The time-figure plates on the horizontal line with "Sunday" are confined by short bars s and studs r .

The advantages of a time-card of this description for letter-boxes will be apparent to those acquainted with the subject.

Having described my invention, I claim and desire to secure by Letters Patent of the United States—

A time-card for letter-boxes, comprising the combination of a metal frame having cut-away places d , an hour-figure plate which is thick-

est where the figure is cast, and which has a thin flange, h , at one end and a thin part, i , at the other end, provided at its extremity with a tongue, k , and at its center with a hole, l , a minute-figure plate resting upon the thin part i of the hour-figure plate, and having at one end a tang, l' , inserted in said center hole, and having at the other end two tangs, n , and a locking-bar to confine said plates, as set forth.

In testimony whereof I affix my signature in the presence of two witnesses.

BRENT McM. REED.
